FOLDING LADDER

Filed March 17, 1928

INVENTOR.
SAMUEL F. WILLIAMS
BY *A. B. Bowman*
ATTORNEY

UNITED STATES PATENT OFFICE

SAMUEL F. WILLIAMS, OF SAN DIEGO, CALIFORNIA

FOLDING LADDER

Application filed March 17, 1928. Serial No. 262,565.

My invention relates to folding ladders and the objects of my invention are: first, to provide a ladder of this type which is convenient for carrying about from one place to another and which may be stored in a small space; second, to provide a ladder of this class which is safe when opened for use; third, to provide a ladder of this class which is self-supporting and may be used as a step-ladder; fourth, to provide a ladder having detachable supports which may be collapsed when not in use; fifth, to provide a ladder of this class in which the latch means is placed at the normal upper end so that it cannot be inadvertently or unknowingly released; and sixth, to provide a ladder which is light yet strong in structure, durable and easily manipulated.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a perspective view of my ladder with the supports attached thereto; Fig. 2 is a fragmentary elevational view of my ladder showing certain parts and portions broken away and indicating by dotted lines the position assumed by various parts of the ladder when the latter is folded; Fig. 3 is an enlarged view of the socket provided for receiving the end of the support member as viewed from the rear of the ladder along the line 3—3 of Fig. 1; Fig. 4 is a sectional view on an enlarged scale of parts of the ladder taken along the line 4—4 of Fig. 2; and Fig. 5 is an enlarged fragmentary view taken along the line 5—5 of Fig. 2.

Similar characters of reference refer to similar parts and portions throughout the several views of the drawings.

The side rails 1, rungs 2, pivot pins 3, sockets 4, support 5, latch 6, reinforcements 7 and 8, form the principal parts and portions of my folding ladder.

The side rails 1 are made preferably of suitable lengths of U-shaped channel iron, the concave surfaces of which face inwardly. The rungs 2 are also made of U-shaped channel iron the length being chosen to suit the width of ladder required and the width of the channel iron being such that the ends of the rungs may be pivoted within the side rails by means of the pivot pins 3, as illustrated in Fig. 5. The rung 2a at the top of the ladder is made of somewhat narrower channel iron so as to provide space for the latch member 6 which, as shown clearly in Fig. 4, occupies the position between the side rail 1 and the rung 2a, being pivoted by means of the pin 6a to the inner side wall of the rail at its one end and having at its free end a slot 6b which is adapted to engage the lug 2b secured to the side of the upper rung 2a intermediate its ends. Thus when the ladder is opened up such that the rungs occupy a substantially horizontal position, the slot 6b of the catch member 6 will engage the lug 2b, the catch occupying the oblique position shown in Fig. 1, thereby locking the ladder rigidly in an open position. In order to prevent the lug 2b from hindering the ladder from being completely collapsed, I provide the slot 1a in the side wall of the rail 1 so that when folded the lug 2b may be accommodated therein as shown in Fig. 2. In this position the catch 6 will occupy a substantially vertical position between the rung 2a and the side rail 1. Rigidly secured to the upper rear ends of the side rails, preferably by means of rivets 4c, I provide the sockets 4 having a substantially flat base portion 4a and obliquely positioned integral socket portions 4b.

The socket portions 4b, while being inclined inwardly with respect to the rails 1, also extend slightly rearwardly thereof so that when the supports 5 are inserted therein they extend rearwardly of the side rails and form with the ladder a four-point support. The supports 5 are preferably in the form of rods or pipes and they are pivotally secured together by means of a pin 5a at a point approximately two-thirds the distance from their lower ends so that when inserted in the

sockets 4b they effectively brace each other and when removed therefrom they may be collapsed so as to occupy a minimum space. The reinforcing members 7 are inserted in the lower end of one side rail and the upper end of the other side rail and provide stops for the lower and upper rung so that when opening up the ladder the rungs cannot describe a greater arc than ninety degrees. Knobs 7a are provided at the lower end of the ladder for presenting a rounded supporting surface. Substantially wedge shaped reinforcing members 8 are provided at the other end of the side rails the object thereof being to prevent accidental deformation of the channel-shaped rails. The portions of the side rails extending above the upper rung and below the lower rung are made slightly less than the length of the rung in order that in folding the ladder the ends of the rails in which the ends of the reinforcing members 8 are inserted will lie substantially flush against the inner ends of the reinforcing members 7. By placing the latch member 6 at the normal upper end of the ladder, any accidental dislodgment of the latch unknown to the user is prevented, and the ladder is therefore much safer than would be the case, were the latch placed lower down.

Though I have shown and described a particular construction, combination and arrangement of parts and portions, I do not wish to be limited to this particular construction, combination and arrangement but desire to include in the scope of my invention the construction, combination and arrangement substantially as set forth in the appended claims.

Having thus described my invention, what I claim as new and desire to secure by Letters Patent is:

1. In a folding ladder, a pair of channel shaped rails, a plurality of rungs, the ends of said rungs adapted to extend within said channel shaped rails and pivoted thereto, an upper rung of width narrower than said other rungs, a catch member pivotally secured to the upper end of one of said guide rails and adapted to engage a lug positioned intermediate the ends of the upper rung for holding the ladder in open position, said rungs being adapted to be wholly enclosed within said guide rails when the ladder is in its folded position, said upper rung forming with the adjacent channel wall a space for receiving said catch member.

2. In a folding ladder, a pair of channel shaped rails, substantially channel shaped rungs pivotally secured at their ends to said rails, the ends of the rungs extending within said rails, an upper rung of said ladder being of a width narrower than said other rung and provided with a lug at one side intermediate its ends, a substantially flat catch member pivotally secured to the upper end of one of

said rails at a point above said upper rung, the free end of said catch member being provided with a slot adapted to engage with said lug and hold the ladder in open position, said catch member being adapted to fold between said upper rung and the side wall of said rails when the ladder is in a closed inoperative position.

In testimony whereof, I have hereunto set my hand at San Diego, California, this 9th day of March, 1928.

SAMUEL F. WILLIAMS.
